Primary Examiner—Mitchell Siegel

(**) Term: **14 Years**

(57) **CLAIM**

(21) Appl. No.: **29/124,905**

The ornamental design for an upstanding open air cooler with side waves, as shown and described.

(22) Filed: **Jun. 12, 2000**

DESCRIPTION

(51) LOC (7) Cl. **15-07**

FIG. 1 perspective view of the present invention;

(52) U.S. Cl. **D15/81**

FIG. 2 is a front view of the present invention;

(58) Field of Search D15/81-88, 79;
D6/470-472, 479, 477, 449, 478; 312/116,
138.1, 236; 62/246, 251, 248, 449, 440,
441

FIG. 3 is a right side view of the present invention, the left

(56) **References Cited**

side view being a mirror image thereof;

U.S. PATENT DOCUMENTS

FIG. 4 is a top plan view of the present invention;

D. 352,850 * 11/1994 Fujii D6/479

FIG. 5 is a bottom plan view of the present invention; and,

FIG. 6 is a rear view of the present invention.
